UNITED STATES PATENT OFFICE.

WILLIAM P. CLARK, OF BELMONT, NEW YORK.

CIRCULAR SAW MILL.

SPECIFICATION forming part of Letters Patent No. 294,442, dated March 4, 1884.

Application filed November 26, 1883. (No model.)

To all whom it may concern:

Be it known that I, WILLIAM P. CLARK, a citizen of the United States of America, residing at Belmont, in the county of Allegany, 5 and State of New York, have invented certain new and useful Improvements in Saw-Mill Feed and Gig Works, of which the following is a specification, reference being had therein to the accompanying drawings.

10 This invention relates to an improvement in saw-mill feed and gig works; and it consists in the peculiar combinations and construction and arrangement of parts hereinafter described, and then pointed out in the claims.

15 In the accompanying drawings, Figure 1 shows a plan of a saw-mill constructed according to my improvement. Fig. 2 is a side view of part of the gearing, showing the mode of changing the feed mechanism. Fig. 3 is an 20 end view, and Fig. 4 is a side view, of the carriage, ways, &c.

A is the saw-arbor, mounted in suitable bearing, *a*, on the frame, and carrying the drive-pulley B, friction-pulley C, and the feed-cone D. At I is the feed-shaft, working in bearings on the front end of the husk and carrying the balance-wheel H, small-friction-wheel F, and the feed-cone G, connected by a band (not shown) with the cone D, in the usual manner.

25 J is an intermediate shaft, carrying on one end a gear-wheel, K, which meshes with the larger gear-wheel L on the drum-shaft M. On the other end of the shaft J is a friction-pulley, E, placed in line with the pulleys C and F.

30 The shaft J is hung in an eccentric, S, (see Fig. 2,) which is connected by arms *s*, rod *S'*, arm *S''*, and the shaft T to the sawyer's lever V. By the movement of this lever the eccentric will be rolled in its bearing, and the shaft J

35 thus moved brings the friction-wheel E into contact with the friction-wheels C or F, according as it is desired to feed or gig the carriage. The shaft M, which works in bearings *m* in the mill-timbers W, carries a drum, N, having a spiral groove, around which passes the rope O, which also passes over adjustable sheaves P P, having their bearings in yokes Z, one of which is secured in a suitable guide, I', near each end of the track, W, on which the

40 carriage runs. The yokes Z, carrying the sheaves P, are fastened adjustably in the guides I' by means of screw-bolts Q, having nuts *q* at

the ends of the guides I', mainly for the purpose of taking up the slack of the rope as it lengthens, and thus keep it taut. The rope O is attached to the carriage R by being passed through eyes in the connecting-arms *r*, and its ends are fastened one to each end of the drum. The rope is so wound on the drum that it is full of rope at all times, and there is no danger 55 of the rope slipping. When motion is communicated to the mill and the lever V is moved toward the saw-arbor, the change in the position of the eccentric will bring the friction-wheel E into contact with the feed friction-wheel F, and the shaft J will thus be revolved toward the sawyer, and the gear K, meshing with the gears L, will revolve the shafts M and drum N in the opposite direction, and move the carriage R toward the saw. The reverse 60 movement of the lever V will change the position of the eccentric, and thus bring the friction-wheel E in contact with the friction-wheel C, which will reverse the motion of the shaft J and gig the carriage.

75 It will be observed that the yokes Z, carrying the pulleys P, being secured only by the screw-bolts Q and nuts *q*, will swing sidewise to a certain extent and thus accommodate themselves to the varying positions of the rope 80 as it winds on or unwinds off the drum. As the pulleys P are usually about sixty feet apart, or thirty feet from the drum, this swinging of the yokes is not actually necessary, if the groove in the pulley is properly proportioned; but with the swinging of the yoke 85 there is less necessity for deep grooves in the pulleys, and there will be less friction on the rope. In some cases I propose to set the yokes Z one near each side of the track, instead of the center, as shown.

90 I have shown a rope, but it is evident that a belt or a chain may be substituted for, and would be an equivalent for, the rope, and that instead of there being one rope, as shown, two 95 ropes may be employed, one end of each being connected to the carriage, which would produce substantially the same effect as if but one rope were employed, and would be an equivalent arrangement. By this arrangement and construction a rope-feed can be readily operated at a fast speed without the independent engine which is usually required in running rope-feeds at their full speed.

Without the use of the gearing and friction wheels shown and the fly-wheel H a very rapid gigging motion cannot be given to the carriage, because it cannot be arrested and reversed on account of the slipping of the friction and belts; but the fly-wheel H on the end of the feed-shaft acquires such momentum that it will stop and reverse the carriage under the highest gigging speed. I am thus enabled to run the carriage nearly or quite as fast as it is practical to do with independent engines without the extra cost and trouble attending the use of such engines.

What I claim as new is—

15 1. The combination, with a saw-mill carriage, of a revolving drum and a rope connected with the carriage and passing over pulleys at the opposite ends of the track, and having its ends connected with the drum, substantially as described,

20 2. The combination, with a saw-mill carriage and a rope connected therewith and passing over a pulley at each end of the track, of a spirally-grooved revolving drum having the ends of the rope made fast at its opposite ends, substantially as described.

25 3. The combination, with a saw-mill carriage, of a rope connected therewith and passing over a swinging pulley at each end of the track, and of a revolving drum having the opposite ends of the rope connected thereto, substantially as described.

30 4. The combination, with a saw-mill carriage, of the pulleys P, mounted in yokes, as 35 Z, constructed to be adjusted lengthwise of

the ways, the drum N, and the rope O, connected to the drum and carriage and passing over the pulleys P, all substantially as shown and described.

5. In a rope gig and feed works of a saw-mill, the rope O, connected to the carriage and passing around pulleys P and drum N, said drum being connected with the saw-arbor by gearing, substantially as described, constructed to give the drum and rope different speeds 40 in opposite directions, in combination with the fly-wheel H, arranged on the shaft I of the feeding-pulley, whereby the momentum of said fly-wheel prevents the slipping of the friction and belts, substantially as described. 45

6. The combination, in a saw-mill, of the rope O, connected to the log-carriage and running over the pulleys P and wound around the drum N, said drum being connected by its shaft M and gearing K L with the friction-wheel E, mounted on the shaft J, carrying gear K, and adapted to be alternately thrown into contact with the friction-wheel C on the saw-arbor, and with the friction-wheel F, running on the shaft I, and the fly-wheel H, mounted 50 on said shaft, substantially as and for the purpose specified. 55

In testimony whereof I affix my signature, in presence of two witnesses, this 6th day of November, 1883.

WILLIAM P. CLARK.
